UNITED STATES PATENT OFFICE.

VAN C. McCROBY, OF LEONIA, NEW JERSEY, ASSIGNOR TO McCROBY STORES CORPORATION, OF NEW YORK, N. Y., A CORPORATION OF DELAWARE.

DISPLAY COUNTER.

Application filed October 28, 1927. Serial No. 229,415.

This invention relates to counters for the display of goods to be sold and, more particularly, to the partitioning of such counters, and to devices for holding counter partitions in place.

In counters or tables of the character indicated, the goods to be displayed for sale rest on a false bottom composed of small blocks, the upper surfaces of which are approximately level with each other and are usually level with an encircling or enclosing wall about the edge of the table. These blocks have heretofore been spaced from each other sufficiently to permit the insertion of a vertical sheet of glass which extends upwardly above the upper surface of the blocks to form partitions and divide the surface of the false bottom into a number of small compartments. In thus dividing the surface of the false bottom, the blocks have been so arranged and spaced as to receive main partitions that extend entirely across the table or counter, usually in a transverse direction, and divide the surface into main compartments. To divide the long compartments thus formed into smaller compartments, it has heretofore been necessary to form the bottom of each main compartment of a number of small blocks so that vertical division walls might be inserted therebetween. This necessitated the use of a large number of blocks and limited the area of the sub-compartments thus formed to the exact sizes of the boxes that could be fitted into the lengthwise compartment.

These disadvantages and limitations are avoided by my present invention, one object of which is to enable sub-compartments to be formed, of any desired width, on a single block surface.

Another object of the invention is to provide a partition holding or anchoring device that may be readily and quickly installed at any desired position.

A further object of the invention is to provide a partitioned counter of simple construction, having a minimum number of false bottom blocks, that permits the area of the counter to be divided into compartments of any desired width.

With these and other objects in view, the invention comprises the counter and partition construction and the anchoring or holding means described and set forth in the following specification and claims.

The various features of the invention are illustrated in the accompanying drawing, in which;

Fig. 1 is a vertical sectional view through a portion of a counter, showing an anchoring means embodying a preferred form of the invention.

Fig. 2 is a plan view of the counter and anchoring means shown in Fig. 1, and

Fig. 3 is a perspective view of the anchoring means shown in Figs. 1 and 2.

Referring to the drawing, the surface of the counter is laid with a number of false bottom blocks 10, 11 and 12 which, as indicated in Fig. 2, preferably extend from one side of the counter to the other. These blocks 10 to 12 may be of the usual hollow or inverted box-like construction, covered with muslin or other fabric 13. The blocks 10 to 12 are spaced from each other to form vertical channels 14 and 15 to receive and support dividing partitions 16 and 17 which are usually of plate glass. These partitions 16 and 17 rest on the upper surface 18 of the counter or table and project above the upper surface of the blocks 10 to 12 to the height desired for the partition. As shown in Fig. 2, the partitions 16 and 17 divide the surface of the counter into long, transverse compartments 19.

To subdivide the compartment 19 into sub-compartments of the desired size, transverse partitions 20 and 21, which may also be of plate glass, are positioned to extend to the opposed surfaces of the partitions 16 and 17, and to rest on the upper surface of the blocks 10, 11 and 12, respectively. The partitions 20 and 21 are of a height equal to the distance from the upper surface of the blocks 10 to 12 to the upper edge of the partitions 16 and 17 or, if desired, may be made somewhat less or greater than this width.

To hold the partitions 20 and 21 in their proper position and to prevent them from being overturned, or displaced sideways, anchoring means 22 and 23 are provided, one at each end of the partition 20 or 21. The anchoring means 22 and 23, which are duplicates of each other, are so arranged that they may be placed at any desired point on the length of the blocks 10, 11 or 12, and thereby permit successive partitions 20, 21, to be placed as near each other, or as far apart from each other as desired. In the particular form shown in the accompanying drawing,

the anchoring means are formed of a single sheet 24 of metal, having a portion 25 of approximately the width of the partition 20 or 21, and having a pair of wings 26, 27, 5 struck up outwardly from the side edges of the portion 25, so that the end portion of a partition may be inserted and held therebetween. The lower portion of the plate 24 is widened and provided at its lateral, lower 10 extremities with a pair of teeth 28 and 29 which project in the same direction as the wings 26 and 27.

In dividing the compartment 19 into sub-compartments, a pair of anchoring means 15 are so positioned, one at each side edge of the block the surface of which is to be divided into sub-compartments, that the lower portion of the plate 24 extends below the upper surface of the respective block 11 and 20 lies tightly against the partition 16 or 17. In this position, as shown in Fig. 1, the teeth or prongs 28 and 29 will be pressed into the side surface of the block 11 and thus hold the anchoring device from tilting or sliding 25 lengthwise of the block. The anchoring means may be very easily inserted at the desired position by placing it with the wings extending downwardly against the upper surface of the block 11, and the teeth inserted 30 between the partition 16 or 17 of the block 11, as indicated in dotted lines in Fig. 1. When the anchoring device is brought to an upright position, the prongs will be pressed into the block to an extent 35 sufficient to securely anchor it.

It will be apparent from the above description that instead of the large number of blocks required for a single long compartment under the former manner of sub-dividing such compartments, under my present invention, only a single block of the length of the compartment, and of the desired width, is required. Not only is the 40 number of blocks required for the desired arrangement of sub-divisions thus greatly lessened, but it is also possible to quickly and readily vary the size of, and sets of, 45 sub-compartments without fitting a new assembly of division blocks.

As changes of construction could be made 50 within the scope of my invention, it is in-

tended that all matter contained in the above description, or shown in the accompanying drawing shall be interpreted as illustrative, and not in a limiting sense.

55

Having now described my invention, what I claim as new and desire to secure by Letters Patent is:

1. A display counter having a false bottom formed of a number of long blocks 60 placed side by side and slightly spaced from each other, main partitions projecting from between said blocks vertically above said false bottom to form main compartments, subpartitions resting on the surface of said 65 blocks extending between said main partitions to divide said main compartments into sub-compartments, and anchoring and retaining means having means for retaining said sub-partitions, and means engaging the 70 sides of said blocks between said blocks and said main partitions.

2. A display counter having a false bottom formed of a number of long blocks 75 placed side by side and slightly spaced from each other, main partitions projecting from between said blocks vertically above said false bottom to form main compartments, sub-partitions resting on the surface of said false bottom and extending between said main 80 partitions to divide said main compartments into sub-compartments, and anchoring plates between the ends of said sub-partitions and the side of said main partitions, said anchoring plates having retaining wings enclosing 85 the ends of said sub-partitions and having projections between said partitions and said blocks and projecting towards the sides of said blocks.

3. An anchoring means of the type de- 90 scribed which comprises a flat plate having a narrow vertical portion, vertical wings projecting from each side edge of said vertical portion to engage the end portion of a partition, a widened lower portion on said 95 plate, and a pair of teeth projecting sidewise from the lower edge of said plate in the same direction as said wings.

In testimony whereof I hereunto affix my signature.

VAN C. McCRARY.
